DESIGN FOR A HOBBY HORSE

Clifford B. Dobson, Berkeley, Calif.

Application November 22, 1946, Serial No. 134,995

Term of patent 3½ years

(Cl. D34—15)

To all whom it may concern:

Be it known that I, Clifford B. Dobson, a citizen of the United States of America and a resident of the city of Berkeley, county of Alameda, State of California, have invented a new, original, and ornamental Design for a Hobby Horse, of which the following is a specification, reference being had to the accompanying drawing, forming a part hereof.

Figure 1 is a side elevational view of the hobby horse, showing my new design;

Figure 2 is a plan view of such hobby horse; and

Figure 3 is a view in elevation of the rear end of such hobby horse.

I claim:

The ornamental design for a hobby horse, substantially as shown.

CLIFFORD B. DOBSON.
